[57] CLAIM

The ornamental design for a sword hilt, as shown and described.

DESCRIPTION

FIG. 1 is a front elevational view of a sword hilt, showing our new design;

FIG. 2 is a rear elevational view thereof;

FIG. 3 is a front perspective view thereof;

FIG. 4 is a rear perspective view thereof;

FIG. 5 is a top plan view thereof; and,

FIG. 6 is a bottom plan view thereof.

The broken line showing of a sword blade is for illustrative purposes only and forms no part of the claimed design.

FIG. 1

FIG. 2

FIG. 5

FIG. 6
